UNITED STATES PATENT OFFICE.

JAMES O'DONNELL, OF SAN FRANCISCO, CALIFORNIA.

CAR-BRAKE.

SPECIFICATION forming part of Letters Patent No. 289,128, dated November 27, 1883.

Application filed July 14, 1883. (No model.)

To all whom it may concern:

Be it known that I, JAMES O'DONNELL, of San Francisco, in the county of San Francisco and State of California, have invented a new and Improved Eccentric Spring-Brake, of which the following is a full, clear, and exact description.

The object of my invention is to provide a new and improved spring-brake which can be applied on any locomotive or railway-car, is very effective, and permits of reducing the speed of a train or stopping the train entirely without wearing off the wheels, as all other brakes do in which brake-shoes are pressed against the rims of the wheels to produce sufficient friction to prevent the wheels from revolving.

The invention consists of an eccentric spring-brake disk combined with a frame pivoted below the car-floor in which frame the shaft is journaled, on which the brake-disks are mounted, and on which shaft are mounted two clutch-pulleys, one of which is revolved by a chain or belt from one of the axles. The said clutch-pulleys are pressed together by a powerful spring when the brake-disks are lowered, and thereby the brake-disks are coupled, and the shaft carrying the brake-disks is revolved. As soon as the shaft carrying the two disks is raised a beveled wheel separates the clutch-disks, and the shaft carrying the brake-disks will no longer be revolved.

The invention also consists of various parts and details and combinations of the same, as will be fully described and set forth hereinafter.

Reference is to be had to the accompanying drawings, forming a part of this specification, in which similar letters of reference indicate corresponding parts in all the figures.

Figure 1 is a longitudinal sectional elevation of my improved eccentric spring-brake, on the line $x-x$, Fig. 2, showing it applied on a railway-car. Fig. 2 is a plan view of the same. Fig. 3 is a side view of the eccentric brake-wheel with the covering-plate removed, showing the parts in position when the brake is not applied. Fig. 4 is a like view showing the parts in position when the brake is applied. Fig. 5 is a cross-sectional elevation of Fig. 3. Fig. 6 is a longitudinal sectional ele-

vation of my improved eccentric spring-brake, showing it applied on a locomotive. Fig. 7 is a plan view of the same. Fig. 8 is a detail face view of the clutching mechanism. 55

On the axle A of a car-truck a grooved pulley, B, is mounted, over which an endless chain or wire cable, C, passes, which also passes over a pulley, D, mounted loosely on a shaft, F, journaled in a frame, E, pivoted to the car-truck or to two arms, F', projecting downward from the floor of the car. A pulley, G, is mounted on the shaft F in such a manner that it can turn with and slide on the same. A spring, H, projecting downward 65 from the floor of the car and provided with a slot through which the shaft F can pass, rests against the outer surface of the pulley G and presses the pulley G against the pulley D. Both these pulleys are provided on the adjoining surfaces with clutching devices, so that when the pulleys are pressed together they will engage with each other, and if the pulley D is revolved it will also revolve the pulley G and the shaft F on which it is mounted. 75

A wheel, a, mounted on a short axle journaled between two arms projecting downward from the car, is so located that when the axle F is raised it strikes the beveled flange g of the pulley G, and moves the pulley G from 80 the pulley D, thereby disengaging the two pulleys. A frame, J, is pivoted to two arms, K, projecting downward from the floor of the car, and on the ends of the said frame J rollers J' are pivoted, to rest on the free end of 85 the frame E. A chain, L, connected with the usual brake-shaft, passes over a pulley, L', on the bottom of the car, and the same end of the frame J is connected with a piston-rod, M, connected with a piston in a cylinder, M', on 90 the under side of the car, so that the end of the said frame J can be raised either by means of the piston or by means of the chain L, thereby forcing the opposite end, provided with the rollers J', downward. On each end of 95 the shaft F a hub, N, is rigidly mounted and suitably keyed, which hub is provided with a series of short radial cylindrical arms or spokes, N', each provided with a central aperture for receiving a rod, O, provided in its outer end 100 with a cylindrical head, P, around which heads P and arms O powerful spiral springs R are

coiled, which are secured to the heads P and rest on the hub. If pressure is exerted on the heads P, the stems O will be forced into the apertures in the radial arms N' and in the hub. 5 The arms N', with their rods O and heads P, are surrounded by a cylindrical casing, S, provided with an outer end plate, T, which cylindrical casing or rim is provided in its flat side with a large central aperture, to permit 10 the shaft F to move up and down, these devices constituting the brake-wheels or disks. Plates U, projecting downward from the bottom of the car-floor, rest against the inner sides of the casings S and close the above-mentioned openings in the same, the plates being provided 15 with longitudinal slots, to permit of vertical movement of the shaft F, which plates keep the dust and dirt out of the casings. The outer rim of the cylindrical casing S is beveled toward the inside, so that it will not strike 20 against switch-rails, frogs, &c. The plates U, before mentioned, also assist to keep the casings I steady and in position. If the brake is to be applied, that end of the frame J to which 25 the chain L or the piston-rod M is fastened is raised either by creating a vacuum in the piston, or by admitting compressed air or steam into the cylinder, or by winding the chain L upon the brake-shaft. If the said end of the 30 frame J is raised, the other end, carrying the rollers J', will be depressed and will press down the free end of the frame E, in which the shaft F is journaled, and thereby the rims of the casings S will be pressed on the rails W, and the rods O and the heads P will be pressed 35 into the apertures in the radial arms and in the hubs, and the springs R will be compressed. As the hub N is revolved, the several springs R will be compressed successively as the several rods or stems O are successively passed 40 into the corresponding radial arms, N', of the hub. If the shaft F is pressed downward, the clutch-pulley G will be moved from the wheel a, and thus the spring H is enabled to press 45 the clutch-pulley G against the pulley D, so that the two will engage. The clutch-pulley D is being continually revolved from the pulley B on the axle A, as shown in Figs. 1 and 2, or from the pulley on the axle of the driving-wheels of the locomotive. If the pulley 50 D is revolved the pulley G and the shaft F will also be revolved, and will revolve the casings S, and the rims of the casings are pressed against the rails by the springs R, and thus sufficient friction is produced to 55 retard the speed of the train or to stop the train entirely. If the brakes are to be loosened, the chain on the brake-shaft is released and the outer end of the frame J descends, and its inner end, which is connected with the frame E by a chain, d, is raised and raises the said frame E, thereby raising the cylindrical casings S from the rails when the brakes are operated by hand. As the shaft F moves upward, the wheel a, the edge of which is beveled, comes in contact with the beveled flange 60 65

g of the pulley G and moves the said pulley G from the pulley D, thus disconnecting them, so that the pulley G on the shaft F will no longer be revolved with the pulley D. 70

In the construction shown in Figs. 6 and 7 the shaft F is not journaled in the frame E. It is journaled in the frame J, and the pulley D is operated from the driving-wheel instead of from the truck-wheel; otherwise the construction and arrangement are the same. 75

I do not abandon or dedicate to the public any patentable features set forth herein and not hereinafter claimed, but reserve the right to claim the same either in a reissue of any patent that may be granted upon this application or in other applications for Letters Patent that I may make. 80

Having thus fully described my invention, I claim as new and desire to secure by Letters Patent— 85

1. The combination, with a brake-wheel mounted on a shaft journaled in a frame pivoted below the car-bottom, of devices for pressing the brake-wheel on the rail, fixed and loose clutch-pulleys on the shaft of the brake-wheel, and a driving chain or belt for rotating one of the clutch-pulleys from one of the axles of the locomotive or car, substantially as herein shown and described, and for the purpose 95 set forth. 90

2. The combination, with a brake-wheel journaled in a frame pivoted below the car-bottom, of loose and fixed clutch-pulleys on the shaft of the brake-wheel, devices for revolving one of the clutch-pulleys from one of the axles of the car or locomotive, a spring for pressing the clutch-pulleys together when the brake-wheel is lowered, and a device for separating the clutch-pulleys when the brake-wheel is raised, 105 substantially as herein shown and described, and for the purpose set forth. 100

3. The combination, with the brake-wheel mounted on the shaft F, pivoted in the frame E, of devices for revolving the shaft of the brake-wheel from one of the axles of the locomotive or car, the pivoted frame J, having one end resting on the frame E, and devices for raising that end of the frame J opposite the one resting on the frame E, substantially as herein 110 shown and described, and for the purpose set forth. 115

4. The combination, with a brake-wheel mounted on the shaft F, journaled in the frame E, pivoted to the car-bottom, of the frame J, pivoted below the car-bottom, devices for raising one end of the frame J, the rollers J' on the opposite end of the frame J, which rollers rest on the frame E, and of devices for revolving the shaft of the brake-wheel from one of the 120 axles of the locomotive, substantially as herein shown and described, and for the purpose set forth. 125

5. The combination, with the shaft F, journaled in a frame pivoted below the car-bottom, of brake-disks mounted on the ends of the same, a loose clutch-pulley, D, around which a driv- 130

ing chain or belt passes, which also passes around a pulley on one of the axles of the car or locomotive, a sliding clutch-pulley, G, the spring H, and the beveled wheel a, substantially as herein shown and described, and for the purpose set forth.

6. The combination, with the shaft F, journaled in a frame pivoted below the car-bottom, of the casings S, surrounding the radial arms 10 or spokes of the hubs mounted on the ends of

the shaft F, which casings S are provided with central apertures, slotted plates U, adjoining the inner sides of the casings, and of devices for revolving the shaft F, and devices for pressing it downward, substantially as herein shown 15 and described, and for the purpose set forth.
